UNITED STATES PATENT OFFICE.

JOHN JAMES HEYWOOD, OF FALL RIVER, MASSACHUSETTS.

BAND FOR DRIVING SPINDLES.

SPECIFICATION forming part of Letters Patent No. 367,041, dated July 26, 1867.

Application filed February 16, 1887. Serial No. 217,787. (No model.)

To all whom it may concern:

Be it known that I, JOHN JAMES HEYWOOD, of Fall River, county of Bristol, and State of Massachusetts, have invented a new and useful Improvement in Bands for Driving Spindles, &c.; and I do hereby declare the following specification, taken in connection with the accompanying drawings, forming a part of the same, to be a description thereof.

10 This invention relates to bands for driving spindles, &c.; and the improvement consists in providing the band with means whereby the ends of the band may be conveniently and quickly pulled through the body of the band, 15 so that the strain upon the band will cause its ends to be held by the gripping force of that part of the body of the band which surrounds the ends, as hereinafter described and claimed.

It also consists in the improved method of 20 fastening the ends to each other, hereinafter described.

The object of the invention is to enable the ends of the band to be conveniently and securely fastened to each other, and so that there 25 will be no salient projections where the ends are joined to interfere with the smooth running of the band, as there would be were the ends tied together in the ordinary manner.

In the accompanying drawings, Figure 1 30 shows a braided band provided near its ends with wire loops passed longitudinally through the body of the band. Fig. 2 represents a braided band which has a loop of wire near one end, and at the other end has a loop 35 formed by passing the end of the band itself back through its body. Fig. 3 shows one end of a twisted band supplied with a wire loop in accordance with the invention. Fig. 4 represents one of the wire loops. Fig. 5 represents 40 both ends of the band shown in Fig. 1 pulled through its body. Fig. 6 represents a portion of a band after the ends are joined ready for use. Fig. 7 represents the ends of the band shown in Fig. 2 pulled through its body. Fig. 45 8 shows a part of said band after its ends are joined ready for use.

A is the band, which may be braided or twisted, as are bands in common use.

B B' are the loops or hooks, which may be of 50 metal, cord, or other suitable material. The loops shown in Fig. 1 are of wire, and are passed

longitudinally through the body of the band near its ends a a' for the distance of an inch or more, the length of the band between the points a a' where the loops emerge being such 55 that when its ends are properly joined the band shall be just the desired length. In the condition shown in Fig. 1 the bands are designed to be sold to the trade and supplied to mills.

60 When the band is to be applied to driving spindles, it is passed around the "drum" of the machine and around a spindle-whirl. The end a is then passed through the loop B', and by said loop is pulled longitudinally 65 through the body of the band, and the end a' is passed through the loop B, and by it is pulled longitudinally through the body of the band, as shown in Fig. 5. The ends a a' are then pulled upon to bring the points a a' 70 together, and are then cut off where they emerge, leaving the band with its ends joined, as in Fig. 6.

Instead of securing the ends of the band by pulling them through, as shown in Fig. 5, 75 they may be returned upon themselves, be interlocked, and be pulled back through the body. The band shown in Fig. 2 is particularly arranged for fastening the ends in this manner. Near the end a the band is provided 80 with a loop, B, as in Fig. 1; but the end a' is returned upon itself, and by means of a wire loop or other suitable device has been pulled back through the body of the band, making a loop, B'. In this condition the bands may be 85 supplied to the trade and consumers. To secure the ends of this band, it is only necessary to pass the end a through the loop B', then back through the loop B, and by said loop pull the end through the body of the band, as shown 90 in Fig. 7, and then finally to pull upon both the ends a a' to bring the points a a' together. The ends are then cut off where they emerge, leaving the band with its ends joined, as shown in Fig. 8.

95 I prefer to make the wire loops B B' of spring-
stock, so that when they are in place in the band their spring force, which tends to spread their ends and to make the loop assume the shape shown in dotted lines at Fig. 4, will ma-
terially assist in retaining the loops in the 100 band against accidental detachment.

By fastening the ends of the band as hereinbefore described, they will be prevented from any slipping by the gripping force of that part of the body of the band which surrounds the ends when the band is under strain or tension.

The distance longitudinally of the band between the points a^2 a^2 being regulated to produce the desired length of band when the ends 10 have been properly joined, such junction can be effected by unskilled labor without any danger of the band being too long or too short when applied.

What I claim, and desire to secure by Letters Patent, is—

1. As an improved article of manufacture, a band for driving spindles, &c., which is provided with terminal hooks or loops, substantially as described, for drawing the ends of the band through its body, substantially as set 20 forth.

2. As an improved article of manufacture, the band A, having therein the longitudinal spring-wire loops, substantially as and for the purposes specified.

JOHN JAMES HEYWOOD.
